DRYING APPARATUS

Charles L. Gehnrich, Elmhurst, N. Y.

Application March 13, 1939, Serial No. 261,471

3 Claims. (Cl. 34—24)

This invention relates to apparatus for removing volatile substances from moving webs and more particularly to an apparatus for drying ink on webs of the type used in printing newspapers, magazines or the like.

An object of the invention is to provide an apparatus for rapidly drying ink on traveling webs so that the web can be immediately subjected to further printing or folding operations.

Another object is to provide for the rapid drying of the inks used in color printing so that the additional colors may be superimposed thereon without delay.

A further object is to provide for the rapid drying of inks in high speed presses, particularly in high speed color presses so that the speed of printing need not be reduced to afford time for the ink to dry between the various printings.

In systems of this type it has been found that passing the paper web in close relationship to a heating unit does not produce the desired result for the reason that the volatile constituents of the ink driven from the paper cause an insulating layer of vapor to form immediately adjacent thereto, which effectively blocks heat transfer from the printing element to the paper, thereby necessitating either an increase in time of exposure to the heating element which reduces the speed of operations or the use of extremely high temperatures with a resulting fire hazard. Furthermore the fire underwriters require the removal and discharge to the atmosphere of a specified minimum quantity of air, dependent upon the quantity of volatiles removed from the paper.

It is accordingly the further object of the present invention to provide a drying system which effectively removes the insulating layer of volatiles from association with the web under treatment to thereby attain greater efficiency in drying while permitting the use of lower temperatures.

Another object is to provide a system of the above type which operates effectively and complies in all respects with the underwriters' specifications as to air discharge.

Although the novel features which are believed to be characteristic of this invention, are pointed out more particularly in the claims appended hereto, the nature of the invention will be better understood by referring to the following description taken in connection with the accompanying drawings in which a specific embodiment thereof has been set forth for purposes of illustration.

In the drawings,

Fig. 1 is a top plan view of a drying system embodying the present invention.

Fig. 2 is a longitudinal vertical section through the apparatus with parts variously broken away to show the arrangement of ducts.

Fig. 3 is a transverse vertical section taken along the line 3—3 of Fig. 2 and

Figs. 4, 5 and 6 are transverse horizontal sections taken along the lines 4—4, 5—5 and 6—6 respectively, of Fig. 2.

Referring to the drawings more in detail, the invention is shown as applied to an apparatus for the treatment of a web 10 which may comprise the paper web received from a high speed printing press of the type used for printing newspapers, magazines or the like. The web 10, Fig. 2, may be received from a printing roll by which it has been printed on one side, for example, on the under side as shown in Fig. 2. The impression may comprise one of the color components of a multicolor printing job. The web 10, thus printed, is passed around a roller 11 thence upwardly in a housing 12, to be described, and around a second roller 13 on its way to a second printing roll by which an additional color component is to be applied thereto.

The housing 12 includes a receiving section 15 which is shaped to receive the web 10 from the first printing roll and a discharge section 16 through which the web is passed to the succeeding printing roll or to suitable folding or cutting apparatus as may be required. A hot air duct 20 is mounted in the housing 12 at the back of the web, that is on the side opposite the printed surface. This duct 20 is provided with a plurality of apertures 21 which are positioned to direct the heated air received from a source to be described on to the back of the web 10 and into the receiving section 15 of the housing 12. The duct 20 is preferably comparatively thin in section and extends the full width of the web.

An additional hot air duct 25 is mounted in the housing 12 and is provided with a plurality of horizontally extending nozzles 26 which are adapted to direct the hot air from the duct 25 on to the printed surface of the web 10. These nozzles 26 are horizontally spaced for the reason to be set forth and extend over substantially the entire width of the web so that the hot air from the duct 25 is directed across substantially the entire face thereof.

A return duct 28 is also mounted within the housing 12 and is provided with a plurality of laterally extending nozzles 29 which are similar

to the nozzles 26 but are disposed alternately therewith, in a position to withdraw the air laden with volatile vapors from the surface of the web 10. As shown in Figs. 4 and 5 the ducts 25 and 28 are located at opposite sides of the housing 12 with the laterally extending nozzles 26 and 29 in dovetailed relationship extending alternately therefrom.

The housing 12 is also provided with an exhaust duct 30 which is adapted to withdraw air through the spaces between the adjacent nozzles 26 and 29. A certain quantity of air laden with the volatile vapors is accordingly withdrawn from the space adjacent the web 10, through the spaces between the adjacent nozzles above mentioned and is discharged to the atmosphere as will be described.

For supplying the heated air, a heater 40, Fig. 1, of any suitable type such for example as a heater of the type shown in my Patent #2,077,043, may be used. This heater comprises in general an outer housing 41 to which cold air and return air is supplied and which is heated by heat supplied by burners 42 which may be supplied by any suitable type of fuel. The heated air from the heater 40 is passed through a duct 43 to a blower, such as a fan 44, driven by a belt 45 from a motor 46. The fan 44 discharges to a duct 47 leading to the supply duct 25 above mentioned and also to a duct 48 leading to the hot air duct 20.

The return air from the duct 28 is taken through a duct 50 to the intake side of the heater 40 for recirculation. The exhaust air from the duct 30 is taken to a blower 51 operated by a suitable motor 52 whence it is discharged into the atmosphere. The quantity of air so discharged may be controlled by suitable regulation of the motor 52 or by a damper 53. The quantity of hot air supplied to the ducts 20 and 25 may be controlled by regulation of the motor 46. Suitable dampers may also be included in the various ducts to effect independent control of the operation thereof.

In the operation of this device, heated air is supplied to the web 10 through the apertures 21 in the hot air duct 20 and through the nozzles 26, associated with the hot air duct 25. This air may be heated to a comparatively low temperature, such for example as around 400° F. to 800° F., depending upon the type of work involved, and is supplied to a plurality of horizontally spaced portions of the web as the latter is fed upwardly past the various nozzles. The hot air causes the volatile constituents of the ink to be driven off. The volatile laden air, however, is immediately withdrawn from contact with the web through the nozzles 29 and the duct 50 and also through the housing 12 and the duct 30 so that the building up of an insulating layer of volatile matter is prevented. A portion of the heated air thus removed is recirculated by means of the duct 50 just mentioned. A prescribed portion, however, is removed and discharged through the atmosphere by means of the duct 30, this portion being determined in accordance with the underwriters' requirements and in accordance with the desired operating conditions.

Inasmuch as the volatile layer is immediately removed from contact with the web, the drying operation is facilitated and the use of high temperatures is avoided. The temperature of the heated air is preferably maintained sufficiently low so that the web will not burn should it re-

main stationary in the housing 12 for an appreciable period of time, due for example to stopping the presses. Suitable control means may also be provided to shut off the fuel supply to the burner when the press stops. This immediately reduces the gas temperature as the fans 44 and 51 continue to operate.

It is to be noted that the ducts 25 and 28 are tapered in section toward the bottom of the housing. This tapered section is designed to maintain an equalized air pressure in the various nozzles 26 and 29 and to maintain a uniform air flow throughout the apparatus so that the web may be subjected to uniform and controlled conditions of treatment. A sufficient suction is maintained on the housing 12 by means of the blower 51 so that a positive pressure differential is maintained between the outside atmosphere and the interior of the housing, thus preventing escape of the vapors. The pressure differential is preferably maintained as low as possible so as to minimize the quantity of air leaking into the interior of the housing 12 through the various openings thereof.

It has been found that in using this apparatus for drying colored ink on webs received from high speed presses, the drying operation takes place during the time required for the web to pass through the housing 12. This results in a greatly increased speed of printing, particularly when a plurality of colors are to be superimposed and by reason of the efficient drying between printing operations, results in an improved quality of printing. Furthermore the uniform treatment at a comparatively low temperature, prevents surface hardening and cracking of the ink.

Although a specific embodiment of the invention has been set forth above, it is to be understood that the invention is capable of various uses as will be readily apparent to a person skilled in the art. Certain specific terms have been used herein for convenience of description and not as a limitation on the scope of the invention. The invention is only to be limited in accordance with the following claims.

What I claim is:

1. The method of removing volatile constituents from a traveling web passing through a housing, which comprises passing a gas through a heating zone to heat the same to an elevated temperature, supplying said heated gas to said web at a plurality of supply zones spaced along its path of travel in said housing, removing a portion of the vapor laden gases from a plurality of exhaust zones intermediate said supply zones, recirculating said gases to said heating zone, removing the remainder of the vapor laden gases in a direction substantially normal to the web from a plurality of discharge zones located between said supply and exhaust zones and discharging the gases from said last zones to a point external to said housing.

2. An apparatus for removing a volatile constituent from a traveling web comprising a housing through which said web is passed, a hot air duct and an exhaust duct, a set of nozzles in said housing, each nozzle having a mouth extending transversely across said web close to the printed side thereof, said nozzles being spaced along the path of travel of said web, alternate nozzles being connected respectively to said hot air and exhaust ducts to respectively discharge hot air onto said web and to remove vapor laden air therefrom, an air heater connected to

5 said exhaust duct, a blower connected between said heater and said hot air duct constructed and arranged to recirculate heated air through said ducts and nozzles, adjacent nozzles being spaced apart to provide a transverse passage therebetween, a discharge duct communicating with said passages to remove vapors through said 10 passages in a direction normal to said web, and a suction blower connected to said discharge duct to induce a flow of vapors therethrough, said suction means being connected to discharge said gases to an external point.

10 3. An apparatus for removing a volatile constituent from a traveling web comprising a 15 housing through which said web is passed, a hot air duct and an exhaust duct associated with

said housing, a set of nozzles, each nozzle having a mouth extending transversely across the web close to the printed side thereof, said nozzles being spaced along the path of travel of said web, alternate nozzles being connected respectively to said hot air duct and said exhaust duct to respectively discharge hot air onto said web and to remove vapor laden air therefrom, adjacent nozzles being spaced apart to provide 10 passages in said housing therebetween and exhaust means communicating with said passages to withdraw part of the vapor laden air through said passages in a direction substantially normal to the web and to exhaust the same to the atmosphere.

15 CHARLES L. GEHNRICH.
